JEWELRY FINDING

Robert Slayton, 10717 Wilshire Blvd., Los Angeles, Calif.

Filed June 26, 1958, Ser. No. 51,557

Term of patent 14 years

(Cl. D45—1)

Fig. 1 is a top perspective view of a jewelry finding showing my new design;

Fig. 2 is a top plan view thereof;

Fig. 3 is a side elevational view thereof;

Fig. 4 is a left end elevational view thereof; and

Fig. 5 is a bottom plan view thereof.

The ornamental design shown is for a jewelry finding of the scarab-type characterized by the surface carving wherein the generally Y-shaped groove forms an apex approximately two-thirds of the distance from the rear to the front end of the finding with the forward diverging grooves forming an acute angle.

I claim:

The ornamental design for a jewelry finding, as shown and described.
